FRANK E. HOWE, OF NEW YORK, N. Y., AND LINDSAY I. HOWE, OF BOSTON,
MASSACHUSETTS.

Letters Patent No. 77,488, dated May 5, 1868.

IMPROVEMENT IN COMBINED COAL-HOPPERS AND PLATFORM-SCALES.

The Schedule referred to in these Letters Patent and making part of the same.

TO ALL WHOM IT MAY CONCERN:

Be it known that we, FRANK E. HOWE, of the city, county, and State of New York, and LINDSAY I. HOWE, of Boston, in the county of Suffolk, and State of Massachusetts, have invented a new and improved Combined Coal-Hopper and Scale; and we do hereby declare that the following is a full, clear, and exact description thereof, which will enable others skilled in the art to make and use the same, reference being had to the accompanying drawings, and to the letters of reference marked thereon.

This invention consists in combining a coal-hopper with a scale, in such a manner that coal may be dumped directly from the cart which delivers the coal into the hopper of the scale, and weighed, and then discharged into the coal-hole.

The object of the invention is to obtain, by a very simple attachment to an ordinary platform-scale, a means whereby consumers of coal may weigh the same as it is delivered to them, and thereby prevent the fraud of light or short weight which is now almost universally practised by retail coal-dealers. In the accompanying sheet of drawings—

Figure 1 is a side sectional view of our invention.

Figure 2, a vertical section of the same, taken in the line *xx*, fig. 1.

Similar letters of reference indicate like parts.

A represents the levers or beams of any ordinary platform-scale, connected at one end by an upright rod, B, with a graduated beam, C. D is the platform, which is attached centrally by pivots *a* to the levers A, and this platform has a framing, E, secured upon it, which supports a coal-hopper, F, which has a bottom, G, attached to it, at one side, by hinges, *b*. This bottom is held up at its free or disengaged end by a catch or fastening, H, arranged in any suitable way.

Below the hopper F there is a trough, I, which is directly over a hole, J, in the top of the coal-hole. K is a spout, fitted in the hole in the sidewalk, and extending down over the top of the hopper F, as shown in fig. 1.

As the coal is dumped from the cart over the hole in the sidewalk, the coal is conveyed by the spout K into the hopper F, where it is weighed, it being understood, of course, that when the coal is in the hopper F, its whole weight is upon the platform, D.

After the coal is weighed, the bottom, G, is released by moving the catch or fastening, H, and the weighed coal falls through the trough I into the coal-hole.

In those cases where the consumer is not provided with a coal-hole, but only with a vault, the platform-scale may be placed on an elevated platform in the vault, underneath the hole in the sidewalk, all that is required being space underneath to receive the weighed coal as it is discharged from the hopper on the scale.

This improvement may be applied to any of the platform-scales in use.

Having thus described our invention, we claim as new, and desire to secure by Letters Patent—

The arrangement of the hopper F, in the frame E, supported upon the scale-platform D, when such hopper is adapted to discharge the coal into the hopper I, passing directly through the scale-platform D, as herein shown and described.

FRANK E. HOWE,
LINDSAY I. HOWE.
